UNITED STATES PATENT OFFICE

ENOCH B. STEVERSON, OF PORTSMOUTH, VIRGINIA

COIN CONTROLLED SELF-SERVICE OR VENDING MECHANISM

Application filed October 3, 1929. Serial No. 397,102.

This invention relates to a coin controlled or self-service vending mechanism.

It is aimed to provide a novel construction which may utilize as many containers or 5 vending compartments as desired and may also permit the same to be of transparent material and readily observable to determine their contents.

Another object is to provide an exceedingly simple and inexpensive coin controlled means particularly one involving a balanced locking means adapted to be over-balanced and moved to releasing position upon reception of the proper coin.

A further object is to provide a construction wherein the balancing means cannot be operated upon the deposit of a coin smaller than that required for operation.

Various additional objects and advantages 20 will become apparent from a consideration of the description following taken in connection with accompanying drawings illustrating an operative embodiment.

In said drawings:

Figure 1 is a plan view of the device,

Figure 2 is a front elevation,

Figure 3 is a cross sectional view taken on the line 3—3 of Figure 1,

Figure 4 is a longitudinal sectional view 30 taken on the line 4—4 of Figure 1, and

Figure 5 is a horizontal sectional view taken on the line 5—5 of Figure 2.

Referring specifically to the drawings, 10 designates a suitable cabinet or casing which 35 may be made of wood, metal or any other preferred material and also in any desired shape, or size.

Suitably mounted in the casing or cabinet 10 are one or any desired number of containers 11 which are preferably of transparent glass, and for instance an ordinary drinking glass. The top wall 12 of the cabinet has an opening 13 in line with each of the containers 11 and the lower edge portions of such opening 13 are rabbeted at 14 whereby the upper edge of the glass is received and seated. The glasses are held in place by U-shaped supporting brackets 15, which are fastened as at 16 to the top wall of the cabinet.

Within the containers or glasses 11, goods

to be vended may be placed. The same may be poured directly into the glasses or they may be contained in bags deposited in the glasses. Such containers 11 are adapted to be normally closed by plates or closures 17 55 capable of springing horizontally on pivots afforded by rivets 18 fastened to the top wall 12.

Normally the closures 17 cannot be moved from the closed position shown in the drawings because a locking pin member 19 is extended through an opening 20 in the top wall 12 and thence into a recess 21 in the closure 17.

The locking member 19 is carried by a control lever 22 which is pivoted at 23 on a horizontal axis to a bracket 24 depending from the wall 12. In the position shown in full lines in the drawings, the lever 22 is balanced and hence in its balanced or normal condition maintains the locking member 19 elevated.

The lever 22 has a depressed or receptacle portion 25 adapted to receive a coin deposited by a customer through the coin slot 26 75 formed in the top wall 12 and surrounded by a plate 27 on the exterior of the wall 12. A chute 28 is fastened to the under surface of the wall 12 in line with each slot 26, so as to direct the coin into the receptacles or 80 bowls 25.

29 designates a hood secured over each of the coin slots 26 to protect the interior of the cabinet or casing 10 from rain and snow and at the same time prevent the operation 85 of the device by means of sticks that might be otherwise inserted through the coin slot. Said hood is preferably made of sheet metal bent to provide spaced side walls 30 and 31 arranged on opposite sides of the coin slot 26 and having a top wall 32 that is inclined upwardly and rearwardly of the cabinet or casing. The side wall 30 extends rearwardly further than side wall 31 and is provided with a lug or projection 33 extending laterally thereof towards the plane of wall 31, said lug or projection preventing insertion of a stick or other object through slot 26 as hereinbefore stated.

In inserting a coin in the machine the cus- 100

5 tomer places the coin against the outer side of wall 31 and pressing it against the wall slides it rearwardly. When the coin is moved off of wall 31 lug or projection 33 will engage it and pressure of the finger will direct the front edge of the coin against wall 30 and it may then be directed between walls 30 and 31 and into slot 26.

10 When the proper coin has been deposited, it will be retained by the bowl 25 which will overbalance it, moving the same to dotted line position shown in Figure 3 thereby lowering or retracting the locking pin member 19 from notch 21, and releasing the closure 15 17 so that it may be swung laterally to uncover the receptacle 11 and permit removal of the contents.

15 It is obvious that the machine may be made to operate on the deposit of any desired coin.

20 It will be noted that the receptacle or bowl 25 has an elongated slot at 34. Such slot is provided so that a coin smaller than that required to operate the device will pass through the same into the interior of the cabinet, 25 without operating or overbalancing the lever 25.

25 It will be understood that one of the coin control devices is associated with each of the containers.

30 In arranging the devices it is apparent that any number of containers and coin controlled mechanisms may be arranged in each cabinet or casings 10, and furthermore that any number of cabinets or casings 10 may be 35 included in a stand and that they may be arranged in any desired relation, such for instance as step-form, in spaced vertical relation, or otherwise.

35 Various changes may be resorted to provided they fall within the spirit and scope of the invention.

40 I claim as my invention:—

45 1. In combination with a vending machine, a closure therefor, a lever, locking means for the closure controlled by the lever and normally urged to locking position, the closure being swingable in a plane which is perpendicular to the normal position of the locking means, said lever being arranged for 50 engagement by a coin to retract the locking means, and the lever having a receptacle portion to receive the coin, and the engagement of the locking means with the closure limiting the movement of the lever to normal or 55 locking position.

60 2. In combination with a vending machine, a manually operable closure therefor, a lever, a locking pin for the closure controlled by the lever and normally urged to locking position, the closure being swingable in a plane which is perpendicular to the normal position of the locking pin, said lever being arranged for engagement by a coin to retract the locking pin, said lever having a receptacle portion to receive the coin, the engage- 65

70 ment of the locking means with the closure limiting the movement of the lever to normal or locking position, and the receptacle portion having a slot therethrough whereby improper coins may pass through the same. 75

75 3. In combination with a vending machine, a manually operable closure therefor, a lever, locking means for the closure controlled by the lever and normally urged to locking position, the engagement of the locking means with the closure limiting the movement of the lever to normal or closing position, the closure being swingable in a plane which is perpendicular to the normal position of the locking means, said lever being arranged for engagement by a coin to retract the locking means, and the lever having a slot there- 80 through for the escape of improper coins.

85 In testimony whereof I affix my signature.

ENOCH B. STEVERSON.
